Primary Examiner — Derrick E Holland

(57) **CLAIM**

The ornamental design for a solar charging station, as shown and described.

DESCRIPTION

FIG. 1 is a front left side perspective view for a solar charging station, showing my new design;

FIG. 2 is a rear right side perspective view thereof;

FIG. 3 is a front elevational view thereof;

FIG. 4 is a rear elevational view thereof;

FIG. 5 is a left side elevational view thereof; and,

FIG. 6 is a right side elevational view thereof.

The broken lines shown represent environmental subject matter and form no part of the claimed design.
